UNITED STATES PATENT OFFICE.

IGNACY MOSCICKI, OF FREIBURG, SWITZERLAND.

PROCESS AND APPARATUS FOR PRODUCING OXIDS OF NITROGEN BY MEANS OF A ROTARY FLAME.

No. 920,610.

Specification of Letters Patent.

Patented May 4, 1909.

Application filed October 3, 1908. Serial No. 456,009.

To all whom it may concern:

Be it known that I, IGNACY MOSCICKI, electrician, citizen of Russia, residing at Freiburg, Confederation of Switzerland, 5 have invented a certain new and useful Improvement in Processes and Apparatus for Producing Oxids of Nitrogen by Means of a Rotary Flame; and I do hereby declare the following to be a full, clear, and exact 10 description of the invention, such as will enable others skilled in the art to which it app pertains to make and use the same.

In the production of oxids of nitrogen by the electrical process the voltage employed 15 should be as high as possible in order that work may be carried on with a current of low intensity for a given energy consumption and as far as possible the wearing away of the electrodes be avoided. When the rotary flame is employed, the employable voltage, together with the length of the flame and the pressure to which the gas is subjected, is partially determined by the 20 strength of the magnetic field.

25 The effective voltage in a flame rotating in a magnetic field can be increased by increasing the strength of the magnetic field. In order to effect this in a considerable degree electromagnets must be employed, the 30 two poles of which must be as near each other as possible and between which the flame rotates. This only leads up to such practical forms as those in which a metal body is situated in proximity to the one 35 electrode, and forms a part of the electrode or is metallically connected therewith. These adjacently situated parts of the two electrodes do not allow the effective potential in the flame to increase sufficiently 40 when, in the working, ionized gases are between them, as constant short circuitings of the flame occur. In order to avoid this, gases not entering into reaction or relatively cold can be employed for increasing the re 45 sistance between the adjacently situated parts, as they are conveyed between these parts. This resistance can be so far increased by interposing the relatively cold gases that, when the flame is maintained by 50 alternating current, the ignitions recurring at every half period do not take place in the shortest path between the electrodes but over a larger length near where the flame was extinguished. Likewise in cases in

which the attainment of the highest possible concentration without reduction of the yield requires that one electrode shall be constructed as a cooling body, which is at a slight distance from and opposite the other electrode and against which the flame sweeps 55 in rotating, the introduction of relatively cold gases into the central part of the space between the two electrodes, where the distances apart are slightest, renders possible the employment of a high effective voltage, 60 as the occurrence of short-circuit flames between the nearest adjacent points on the two electrodes is avoided and thereby the formation of long rotary flames is insured. 65

The introduction of the previously mentioned auxiliary gases or vapors on the side of the flame opposite to that on which the reaction gases are introduced, and the withdrawal of these auxiliary gases or vapors 70 can be regulated so that the latter, passing 75 as closely as possible to the flame, form the surface of a cone. The great velocity of the gases passing through the flame, which in connection with a continuous rotary flame 80 can be used by employing relatively small 85 sectional areas for given quantities of energy, makes it impossible for the auxiliary gases or vapors to enter the flame. As auxiliary gases or vapors, use is made of such as can be easily separated from the reaction 90 gases, for example aqueous vapor or gases previously enriched with oxids of nitrogen and sufficiently cooled, or such as in the further treatment would in any case have to be added to the reaction gases. For this 95 purpose also gases similar to those coming into reaction may be used. They can be carried off separately from the reaction gases coming out of the flame and be utilized again. From time to time a portion of 100 these gases which is to be replaced by fresh gases, can be conveyed into the flame as reaction gases, in order that the small percentage of oxids of nitrogen which has mixed with the gases in the zone of contact may 105 not be lost.

An apparatus suitable for carrying out the process described above is illustrated by way of example in the accompanying drawing.

Figure 1 is a vertical section, Fig. 2 a plan partly in horizontal section.

Between the two pole pieces *c* and *d* of a

powerful electromagnet which is excited by the two windings *e* and *e* the two electrodes *a* and *b* are arranged in such a manner that the flame rotates under the influence of the 5 magnetic field in direct proximity to the flat electrode *b*. *f* and *g* are respectively the admission and discharge passages for the cooling water for the electrode *a*.

Through the pole piece *c* and the electrode 10 *a* runs a passage *h*, through which the gases are conducted, which are not intended for the reaction in the flame, and therefore flow in between the flame and the outlet passages *l* in the electrode *b*. The gases intended for 15 reaction in the flame are forced through *i* and flow through the annular space which is shut off by the insulating cylinder *k* subsequently passing downward through the flame.

20 The gases introduced into the furnace through *i* and *h* alike pass through the passages *l* into the collecting chamber *m*, whence they are drawn off through a pipe *n*.

The cooling water for cooling the electrode *b* and the discharge passages for the 25 warm gases, is introduced through the pipe *o* and flows away through *p*.

The projecting rib *r* serves for distributing the gases intended for the reaction suitably to the flame. The two pole pieces *c* and 30 *d* are insulated from the electromagnet by two thin insulating layers *s* and *s'*.

t' and *t''* are the two current conductors for the electrodes *a* and *b*. The electrode *b* 35 carries in the center a cone for deflecting the auxiliary gases. The flame rotates—being under the influence of the powerful magnetic field and affected by the direction of flow of the reaction gases—on the free end 40 of the electrode *a* and forms a surface of rotation, which is situated at a slight distance from the upper extremity of the electrode *b*.

The gases entering through the passage *h*, which are not intended to enter into reaction, are introduced in such quantities that they spread out below the flame over the electrode *b* in a conical form the surface of which as nearly as possible reaches the rotating flame.

50 The reaction gases introduced through the passage *i* are deflected by the rib *r* toward the middle, and then caused by the cone formed by the auxiliary gases to flow along its surface toward the outermost parts of the 55 electrode *b*. Although the electrodes *a* and *b* are at a slight distance apart and opposite

to one another no short circuiting of the rotary flame can occur in the shortest path between the two electrodes, because the cone formed by the auxiliary gases prevents any 60 spreading of hot ionized gases in the central part between the two electrodes, so that the resistance in this spot remains high.

Having now particularly described and ascertained the nature of my said invention and in what manner the same is to be performed, I declare that what I claim is:—

1. A step in the process of producing ox- 70 ids, consisting in maintaining electrically a flame between the electrodes; interposing auxiliary cooling gases between the electrodes to increase the resistance and prevent short circuiting and introducing reaction gases to the influence of said flame.

2. A step in the process of producing ox- 75 ids, consisting in maintaining a flame between electrodes; and introducing auxiliary cooling gases within the flame.

3. A step in the process of producing ox- 80 ids, consisting of maintaining a flame between electrodes; introducing auxiliary cooling gases on one side of the flame and introducing reaction gases on the other side of the flame.

4. An apparatus for producing oxid, 85 consisting of a pair of electrodes; a suitable source of current supply connected therewith; means for producing a magnetic field; means for introducing auxiliary cooling gases between the electrodes; and means for introducing reaction gases between the electrodes.

5. In an apparatus for producing oxids, 90 a pair of electrodes, one of which is formed with a conduit for the introduction of auxiliary cooling gases; a suitable source of current supply connected with said electrodes; and means for introducing reaction gases between said electrodes.

6. In an apparatus of the character de- 100 scribed, the combination of a pair of electrodes, one of which is formed with a conduit for the introduction of gas; and means for introducing gas between said electrodes.

In testimony whereof I affix my signature 105 to this specification, in the presence of two witnesses.

IGNACY MOSCICKI.
